UNITED STATES PATENT OFFICE.

CORNELIUS STONER, OF STONY RIDGE, OHIO.

MOVABLE POULTRY-ROOST.

No. 922,061.

Specification of Letters Patent. Patented May 18, 1909.

Application filed November 12, 1908. Serial No. 462,267.

To all whom it may concern:

Be it known that I, CORNELIUS STONER, a citizen of the United States, residing at Stony Ridge, in the county of Wood and State of Ohio, have invented new and useful Improvements in Movable Poultry-Roosts, of which the following is a specification.

This invention relates to movable poultry roosts, and it has for its object to provide a device of this character which is of extremely simple and inexpensive construction, and so designed as to be easily and conveniently kept in sanitary condition, readily removable, and taking up comparatively little space in the henry.

Another object of the invention is the provision of a roost consisting of a body provided with perches and supported on legs whereby the body can be set at any pitch, the legs being foldable so that the parts can be packed in a small space for shipment.

A further object is to provide wheels on one of the legs which are held normally off the floor when the roost is set up and which are lowered into contact with the floor when the roost is to be taken out of the henry for cleaning, the other leg serving as a tongue for guiding the movement of the roost in wheeling it into or out of the building.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1 is a central longitudinal section of the roost when set up for use. Fig. 2 is a transverse section on line 2—2, Fig. 1. Fig. 3 is a perspective view of the front leg or prop. Fig. 4 is a perspective view of the trough at the lower end of the roof. Fig. 5 is a plan view of the perch. Fig. 6 is a perspective view of the end of one of the perches. Fig. 7 is a detail view showing the connection between the front prop and the bracing rod.

Similar reference characters are employed to designate corresponding parts throughout the views.

Referring to the drawing, A designates the

body of the perch which consists of two side members 1 which are spaced apart and connected together by spaced cross pieces 2 that form the bed for the bottom of the body. Secured to the body are perches 3 of any suitable construction which, as shown in Fig. 6, are provided with pins or nails 4 that are adapted to enter openings 5 in the side members 1 of the body, as shown in Fig. 1, so as to removably secure the perches in position. The bottom consists of strips 6 of galvanized sheet metal of suitable length and width and arranged with their inner edges overlapping at 7, Figs. 2 and 5.

The upper edges of the strip 6 that constitute the bottom are bent downwardly into flanges 8, Fig. 1, so as to engage the end cross piece 2 at the top of the body so as to prevent the bottom from sliding downwardly. The outer edges of the strips are bent upwardly into flanges 9, as shown in Fig. 2, to fit against the inner surfaces of the side members 1. These strips are removable from the body so that they can be washed by a broom and water, as occasion requires, or the entire roost can be taken out of the building or hen house and cleaned by playing water from a hose on the bottom of the body.

The body is supported at its rear end by cross legs 10 which have their upper ends secured to a horizontal cross piece 11 and these legs are attached to one of the cross members 2 of the body by hinges 12 which permit the legs to fold backwardly against the bottom of the body when the roost is not set up. The rear legs 10 are held in unfolded position by a brace rod 13 which has one end rigidly secured to the body A at the rear end thereof and the other extremity connected with the cross legs by projecting through the same at the point where they cross and fastened by clamping nuts 15. On the cross legs 10 is a horizontal axle 16 that is provided at its ends with wheels 17 which support the rear end of the roost when the latter is moved from place to place, the wheels being so arranged that when the roost is set up, they will be raised off the floor, and the legs 10 bearing on the floor will insure stability.

The front of the roost is supported by a single prop or leg designated generally by B and consisting of two sections 18 and 19.

Secured to the upper end of the section 18 is a head piece 20 which is attached by hinges 21 to one of the cross members 2 of the body. The sections 18 and 20 are so connected as to permit the front prop or leg to be extended or contracted to vary the pitch of the body of the roost. For this purpose, the sections overlap each other and are slidably connected by collars 23 and the section 19 is provided with spaced openings 24 in any of which a clamping bolt 25 may be inserted, the said bolt passing through the top section 18 of the prop. The hinges 21 are so arranged that the prop can be swung outwardly to throw the lower end to the front of the roost so that the prop can serve as a tongue when the roost is moved from place to place when running on the wheels 17. The front prop is braced from the body by a rod 26 that is hingedly connected at 27 to the middle of the cross piece 2 of the body and is detachably connected at its lower end to the top collar 23 of the front prop so as to steady the prop. The lower end of the rod 26 is formed into a hook 28, Fig. 7, which passes through an eye 29 on the top collar 23 and the hook is held in the eye by a key 30.

A collecting trough C is arranged at the lower end of the body at a point directly under the lower edges of the bottom thereof and said trough is detachably supported so that the droppings that collect therein can be prevented from discharging on the floor and emptied from the trough into a receptacle from time to time. The trough consists of a sheet metal bottom 31 that is closed at one end by a semi-circular head, while the other end is opened so as to permit the contents to be emptied out of the trough. On the head 32 is a handle 33 whereby the trough can be gripped in one hand, while the other hand is placed under the trough adjacent the other end. The headless end of the trough rests in a ring 34 supported by a hook 35 on the body A of the roost while the opposite end of the trough is suspended on a hook 36 on the body, said hook engaging in an apertured member 37 connected with the head 32. To remove the trough, the hook 36 is first detached from the member 37 while one hand is gripping the handle 33, and then the other end of the trough is withdrawn from the ring 34 while the trough is resting in the other hand.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that

the device shown is merely illustrative, and that such changes may be made when desired as are within the scope of the claims appended hereto.

Having thus described the invention, what I claim is:

1. A poultry roost comprising a body normally inclined, supporting legs at the lower end of the body, an axle secured to the supporting legs, wheels on the axle normally raised off the ground when the body is in inclined position, bracing means between the lower end of the body and the said supporting legs, means for hingedly-connecting the legs with the under side of the body, a central prop at the opposite end of the body, means for hingedly-connecting the said prop to the bottom side of the body, a brace detachably connected with the last-mentioned prop and secured to the body, and perches secured to the body.

2. A poultry roost comprising a body normally inclined to the horizontal, a foldable leg section near the lower end of the body provided with ground wheels normally held elevated when the roost is set up, but which ground wheels come into play to admit of trundling the roost when the rear end is lowered and it is desired to move the same from one place to another, a brace between the foldable leg section and the body to hold said leg section in fixed position when the roost is set up and a second foldable leg section near the upper or rear end of the body adapted to form a handle when trundling the body in the manner specified.

3. In a poultry roost, the combination of transversely spaced longitudinal members, cross pieces connecting said members and attached to the lower edges thereof, perches secured to the upper edges of said side members, and plates constituting a bottom and longitudinally disposed with their edge portions overlapped, the upper ends of said plates having downwardly extended flanges to engage the uppermost cross piece to retain the plates in position and the outer longitudinal edge portions of the plate being upwardly bent to engage the inner face of said side members.

4. A poultry roost comprising a normally inclined body formed of side members, cross pieces connecting the side members at their lower edges, perches secured to the upper edges of said side members, and sheet metal plates forming a bottom and supported by said cross pieces, and having their upper ends provided with downwardly extended flanges to engage the uppermost cross piece, and having their outer longitudinal edge portions upwardly flanged, a trough removably fitted to the lower end of the body, foldable leg sections applied to opposite end portions of the body, and braces for retaining the leg

sections in operative position, the rear leg section being provided with ground wheels normally held elevated and adapted to be brought into operative position when the other end of the body is lowered and it is required to move the roost by trundling the same.

In testimony whereof I affix my signature in presence of two witnesses.

CORNELIUS STONER.
